UNITED STATES PATENT OFFICE.

HENRY NIELSON, OF KOLDING, DENMARK, ASSIGNOR TO THE OSBORN MANUFACTURING COMPANY, OF CLEVELAND, OHIO, A CORPORATION OF OHIO.

ROTARY BRUSH.

1,125,153.

Specification of Letters Patent. Patented Jan. 19, 1915.

Application filed August 14, 1912. Serial No. 734,666.

To all whom it may concern:

Be it known that I, HENRY NIELSON, a subject of the King of Denmark, and a resident of the city of Kolding, Denmark, have 5 invented a new and useful Improvement in Rotary Brushes, of which the following is a specification, the principle of the invention being herein explained, and the best mode in which I have contemplated 10 applying the principle, so as to distinguish it from other inventions.

The subject of the present invention is an improved brush of the type usually known as sectional brushes in which a number of 15 sections or segments are securely held between holding members which are adapted to be engaged upon a rotating hub or shaft. The particular feature of the brush to which the present invention relates, is the 20 attachment of the brush sections to the clamping or holding members. It is necessary to provide a secure and yet simple engagement between the brush sections and the clamping members in order to prevent 25 the relative movements of the brush and the clamping members, and it is also desirable to provide a construction which may be quickly and easily assembled without using extra parts, such as pins and other elements 30 usually required in such a device.

To the accomplishment of the foregoing and related ends, said invention, then, consists of the means hereinafter fully described and particularly pointed out in the 35 claims.

The annexed drawing and the following description set forth in detail certain mechanism embodying the invention, such disclosed means constituting, however, but one 40 of various mechanical forms in which the principle of the invention may be used.

In said annexed drawing:—Figure 1 is a side elevation showing one of the clamping members with a brush section in position 45 thereon; Fig. 2 is a section through an assembled brush when in position upon a shaft; Fig. 3 is a side elevation of one of the clamping members; Fig. 4 is a perspective view of one of the spacing lugs, and 50 Fig. 5 is an elevation showing the method of engagement of the base strands of the brush.

In Fig. 1 I show a brush section composed of a plurality of base strands 1, which are twisted together thereby engaging 55 the brush filaments 2 in the usual man-

ner. The brush sections are preferably, though not necessarily, semi-circular. Whatever be the length of the section the base strands are assembled as illustrated in Fig. 5. One of the base wires is of the 60 length of the section, and twisted with that wire are two other wires which are together substantially equal to the length of the section. At the two ends of the section the ends of the base wires are outwardly and 65 oppositely directed, and at the intermediate point where the inner ends of the two shorter wires meet, those meeting ends are also outwardly and oppositely directed. The brush section is held in a clamping 70 element consisting of holding members 4 in the form of disks, which are provided with central circular apertures 5 connected with two outwardly extending slots 6. At intervals, around the disks there are other and 75 smaller apertures 7. The ends 3 of the base strands are so positioned that upon placing the brush section against the disk 4 the ends 3 of the strands enter the apertures 7 and are engaged therein by means 80 of the second holding member which is placed adjacent to the first holding member and in a parallel relation, as shown in Fig. 2. The apertures 7 are large enough to permit the entrance of the ends of the base 85 wires of two adjoining segmental sections. When the disks are so placed, as is their relation in Fig. 2, the oppositely directed ends 3 of the strands are engaged in one of the apertures 7 in the holding members, 90 and it is only necessary to retain the holding members in such relation to securely clamp the brush sections between them.

In order to maintain the disks in the proper relation, spacing lugs or buttons are 95 provided, consisting of enlarged heads 8 and 9 connected by a shank 10, the heads 8 and 9 being larger than the slots 6, while the shank 10 is of equal size thus adapting the lug or button to have its shank inserted 100 in the slots 6 in the two disks when the two heads will engage against the outer sides of the disks and prevent disengagement so long as the button is prevented from disengaging with the slots 6. The disks in this 105 position are then engaged upon a shaft or hub 11, thus preventing disengagement of the buttons; while the disks are prevented from sliding off the shaft by a collar 12 and lock nuts 13.

The present construction is simpler and easier to assemble than the usual construction which necessitates the formation of lugs on the clamping members, or else provision of a number of pins or locking lugs which engage loops formed by the bent-up ends of the strands, such pins then being clamped in the holding members.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a device of the class described, the combination of a clamping element consisting of two holding members provided with similarly disposed apertures, said members being disposed to bring such apertures into register, and a brush section mounted between said holding members and provided with base strands having oppositely directed and outwardly extending end portions adapted to engage in such apertures in said holding members.

2. In a device of the class described, the combination of a clamping element consisting of two disks provided with similarly disposed apertures, said disks being disposed to bring such apertures into register, a brush section mounted between said disks and provided with base strands having oppositely directed and outwardly extending end portions adapted to engage in such apertures in said disks when in register; and means adapted to maintain said disks in register.

3. In a device of the class described, the combination of two spaced members each provided with a circular series of apertures, the apertures in the two members being in register; and a brush mounted between the members and including base wires provided at circularly spaced positions with outwardly and oppositely extending ends adapted to engage the apertures in the respective members.

Signed at Kolding, Denmark, this 12 day of June, 1913.

HENRY NIELSON.
